UNITED STATES PATENT OFFICE.

FRIEDRICH DECKEL, OF MUNICH, GERMANY.

ENGRAVING-MACHINE.

1,106,084.

Specification of Letters Patent. Patented Aug. 4, 1914.

Application filed February 10, 1913. Serial No. 747,249.

To all whom it may concern:

Be it known that I, FRIEDRICH DECKEL, a subject of the German Emperor, residing at Mozartstrasse 17, Munich, Germany, have **5** invented certain new and useful Improvements in Engraving-Machines, of which the following is a specification.

My invention relates generally to engraving machines, and has particular reference **10** to the means for supporting the rotary cutter or cutting tool employed in such machines and to the construction of the cutter itself.

The principal object of my invention is **15** to improve the detail structure of the cutter shaft of engraving machines, and I accomplish this object by making the shaft of two parts, connected by an elastic non-metallic coupling, one part of the shaft carrying the **20** cutter and the other part the pulley for driving the shaft. The coupling should be of such a character, that the vibrations set up in the part of the shaft carrying the pulley will not be transmitted to the cutter-carrying part of the shaft, and the simplest form **25** of coupling includes a gut connection between the coupling members of the shaft parts.

Another object of the invention relates to **30** the structure of the cutter, the cross section of which forms a sector with a center angle of 90° . The engraving point of the cutter lies therefore in the middle axis and is always the same distance from the cutting **35** edges. The result of this is, that on grinding the cutter no eccentric displacement of the engraving point is possible and the cutter always works exactly.

The invention is illustratively exemplified **40** in the accompanying drawing, wherein—

Figure 1 is a part elevational and part **45** sectional view of a portion of an engraving machine embodying my invention. Figs. 2 and 3 are elevational views of the cutter on a greatly enlarged scale. Fig. 4 is a section on the line A—B of Fig. 2.

Referring to the drawing, the character **50** *b* denotes that part of the bi-part shaft which carries the cutting tool *a*. The other part of the shaft is designated *c* and carries the pulley *d*, over which the cord for rotating the shaft passes. The lower end of the shaft part *c* is forked or bifurcated at *e*, and takes over the reduced upper end *f* of the shaft **55** part *b*. The coupling members *e* and *f* are

connected by a section of gut *g*, which serves the purpose of a coupling pin. The shaft part *c* is angular in cross section, and in order that the pulley *d* may be held in adjusted position on the shaft, the pulley is **60** provided with a hub or boss *k* having a key way *i* into which the key *h* is adapted to be inserted.

For the purpose of insuring the smooth **65** operation of the part *b* of the shaft, which carries the cutter *a*, and in order to compensate for the wear on this part of the shaft due to the axial strain thereon, I provide this part of the shaft with an intermediate disk or shoulder *l* working against ball **70** bearings *m* and *n*, which are held against the disk *l* by a flexible follower device. This follower includes a plurality of spiral springs *o*, inclosed by a sectional casing *p*, the lower ends of the springs acting against **75** a plug *q*, while the upper ends of the springs act against the disk *r*, which forms the upper head of the casing *p*. The action of the springs forces the disk *r* with a yielding pressure against the lower bearing balls and tends to keep the collar *l* in **80** intimate contact with both the upper and lower ball bearings. The entire follower device is secured in an outer casing *t* by means of a threaded nut *s*, and is carried in **85** the lower arm *v* of the machine frame *w*. The upper arm *v* of the frame *w* carries the bearing support *x* for the pulley *d*, said arms being pivotally held by the trunnions *z*. **90**

The cross section of the cutter *a* is as shown in Fig. 4 a sector with a center angle of 90° . The engraving point *a'* of the cutter lies therefore in the middle axis *a²* and has always the same distance from the cutting edges *a³*, *a⁴*, which are inclined toward the point *a'* at *a⁵* and *a⁶* (Figs. 2 and 3). **95**

What I claim is:

1. An engraving machine, embodying **100** therein a cutter shaft composed of sections arranged in axial alinement, and a flexible, non-metallic, vibration-absorbing coupling passing directly through adjacent ends of the shaft sections for connecting the same together. **105**

2. An engraving machine, embodying **110** therein a shaft consisting of axially aligned sections, a section of gut passing directly through adjacent ends of said shaft sections to connect the latter together, and a cutting

tool mounted in the free end of said sectional shaft.

3. An engraving machine, embodying therein a sectional shaft, a flexible non-metallic coupling passing directly through adjacent ends of the shaft sections for connecting the latter to each other, a cutting tool carried by one of said parts and means carried by the other of said parts, whereby 10 the entire shaft may be rotated.

4. An engraving machine, embodying therein a sectional shaft, one part of said shaft having a bifurcated end and the other part of said shaft having a reduced end 15 adapted to be connected with said bifurcated end, a gut connection between said ends, a cutting tool carried by one of said shaft parts, and means carried by the other

of said parts, whereby the entire shaft may be rotated.

5. An engraving machine, embodying therein a bi-part shaft, a flexible coupling between the parts of said shaft, means on one of the parts of the shaft whereby the latter may be rotated, a collar formed on 25 the other shaft part, anti-friction bearings adjacent each face of said collar, and means whereby said collar is yieldingly forced into intimate contact with said anti-friction bearings.

In testimony whereof I have affixed my signature in presence of two witnesses.

FRIEDRICH DECKEL.
